CAP CLOSURE FOR BOTTLES AND TUBES

Flora S. Bartlett, The Fairmont Hotel,
San Francisco, Calif.

Filed July 21, 1958; Ser. No. 749,675

2 Claims. (Cl. 215—76)

This invention relates to a dispensing closure for containers such as bottles, collapsible tubes and the like, and has for one of its objects the provision of such a closure, made of metal, and adapted to be permanently, but rotatably, secured on the discharge head of a collapsible dispensing tube of metal or plastic, or to the discharge head of a bottle of glass, plastic, or metal in sealing relation thereto, and which cap is formed with a discharge opening which is positioned to register with a similar discharge opening in said head upon rotation of the cap to a predetermined degree.

Another object of the invention is the provision of a blank of sheet metal formed for drawing into a closure cap on a bottle or collapsible tube in permanently affixed position on the latter but rotatable relative thereto.

A still further object of the invention is the provision of a blank sheet metal having a relatively soft, resilient, coating of plastic covering a side thereof and which blank is adapted to be drawn over the discharge head and opening of a container that may be of hard or relatively soft material such as metal, glass or plastic and permanently secured to such head, with said covering a slidably sealing engagement with the said head.

An additional object is the combination of a bottle or dispensing tube having a discharge head thereon formed with a discharge opening therein, and a dispensing closure of metal permanently but rotatably secured on said head, which closure is formed with an opening therein adapted to be closed by an imperforate portion of said head when said closure is in one position during its rotation, and to register with the opening in said head when said cap is rotated a predetermined degree from said registering position.

Heretofore most caps for bottles or tubes are threadedly secured thereto, or are slipped onto and off the head for closing a discharge opening in the head and for opening it to enable discharge. In these instances the cap or closure is frequently dropped or lost and attempts to secure the cap onto the head have resulted in relatively complicated and expensive structures, and little if any attempt has been made to seal the head against possible leakage.

The present invention is economical and easy to install, and is press sealed onto the head for permitting easy rotation relative to the latter and at the same time effect a fluid seal.

Other objects and advantages will appear in the description and in the drawings.

In the drawings, Fig. 1 is an exploded isometric view of a bottle and a closure therefor.

Fig. 2 is a plan view of the blank from which the closure of Figs. 1, 3 may be formed.

Fig. 3 is an enlarged vertical sectional view taken through the bottle of Fig. 1 when the closure is on the bottle.

Fig. 4 is a reduced size top plan view of Fig. 3.

Fig. 5 is an isometric, fragmentary view of a modified form of the invention disclosed in Fig. 1.

2

Fig. 6 is a fragmentary, side elevational view, partly in section; of a slightly different form of the invention than is shown in Figs. 1, 5.

Fig. 7 is a plan view of the blank from which the closure of Fig. 6 is formed.

In detail, the blank from which a cap such as is seen in Fig. 1 is formed comprises a circular disc 1 of relatively thin sheet metal having a marginal portion 2, a segment of which is removed to form a recess 4 that may extend through an arc of any desired distance, but preferably somewhere between approximately 30 to 90 degrees.

This disc 1 preferably has a relatively yieldable coating 5 of plastic, such as a polyethylene, on one side thereof, and the disc is adapted to be drawn in a suitable die to form the side walls 6 of a cap 7 (Figs. 1, 3) that is adapted to closely fit over and enclose the head 8 of a container 9 so that the plastic coating 5 is against the surface of the head 8. The central portion 10 of the disc is adapted to form the top of cap 7, and the portion intermediate the central portion 10 and marginal portion 2 is adapted to form sides 6 while marginal portion 2 is adapted to be crimped below a shoulder 11 on said head, with a radially outwardly projecting lug 12 integral with said head, and depending from shoulder 11, extending into recess 4.

When cap 7 is formed from disc 1, and is positioned over head 8, it is in relatively close frictional engagement with head 8. The crimping of the marginal portion 2 under shoulder 11 draws the central portion 10 snugly against the outer end surface of the head 8. Plastic coating 5, being slightly resilient, will be under slight pressure to form a fluid tight seal between the axially facing end surface of the head and the portion 10 of the cap, and the fact that this liner or coating extends over the inner sides of the cap and is disposed between the flange formed by marginal portion 2 when the latter is crimped to extend below shoulder 11, provides a pair of relatively soft resilient bearing surfaces yieldably holding the cap tight against the head 8 at all times.

The portion 10 is formed with an eccentrically positioned discharge opening 13 that is adapted to register with the upper open end of an open ended passageway 14 in head 8, the liner end of which passageway communicates with the interior of the container 9. This registration is only when cap 7 is rotated in one direction until the one side 15 of recess 4 engages a side of lug 12. Rotation of the cap 7 in the opposite direction until the opposite side 17 of recess 4 engages lug 12 will result in opening 13 moving to a position well over the imperforate outer end of the head 8.

Head 8 may be formed in two parts secured together in any suitable manner. One part of head 8 may be the cylindrical outer portion against which the cap 7 is seated, and the other part is a central plug 18 having a recess extending axially thereof from end to end and opening radially outwardly, so that the open side is closed by the cylindrical inner surface of said outer portion of the head. This structure enables the formation of the passageway 14, which is the aforesaid recess in its cooperative relation with the said outer portion of head 8. In other words, the container 9 may be formed in the usual manner and by conventional dies, and the plug 18 is merely secured in the mouth or throat of the container with the recess or passageway 14 in a position to register with opening 13 as above described. The axially outer surface of plug 18 is preferably coplanar with the axially outer surface of the head 8.

Fig. 5 shows a structure similar to that of Figs. 1-3 except that the disc from which the cap is formed has an opening 20 that is in the position 21 that is between a

central portion that corresponds with end 10 of Fig. 1 (except for opening 13) and marginal portion 22.

In this form of invention, it is immaterial whether the outer end of the throat in the head of the bottle is open or closed, since the opening 20 is adapted to register, at one end of the rotary movement of the cap, with an opening 23 in the side of the head.

Lug 24 is similar to lug 12 and recess 25 in the marginal portion 22 is the same as recess 4 in cap 7.

With the invention as disclosed in Fig. 5, the cap may be lined with plastic the same as in the case of cap 7, and it functions in the same manner. Discharge of the contents of the container is from the side of the head instead of from the end.

Figs. 6, 7 show a modification of the structure disclosed in Fig. 5. The blank 26 may be exactly the same as the one that forms the cap shown in Fig. 5, except that there is no marginal recess in the marginal portion 27.

The discharge opening 28 is formed in the portion that becomes the side wall of the container, and the head 29 of the container has a plurality of equally spaced radially directed openings 30 therein, with the space between adjacent openings 30 being substantially greater than that of opening 28.

Inasmuch as the inner plastic coating 32 forms a snug friction fit between the head and the cap, the latter will stay in the position to which it is rotated, and the user can readily see when the opening 28 is in register with any of the openings 30 and when it is disposed over an imperforate portion of the head between an adjacent pair of said openings.

The container, when closed against discharge of the contents, can be safely carried in a purse or pocket because the cap will not rotate to a discharge position unless purposely turned on the head.

In Figs. 1 and 6 the bottle or container is indicated as being of plastic material, but in any of the examples it may be of metal, or glass, or of any other suitable material.

It is pertinent to note that in each of the examples the cap is of a ductile metal and while in some instances the plastic inner coating may not be essential, it enables the employment of cap structure generally of the character disclosed where heretofore it has not been possible from a practical standpoint.

This plastic liner, being substantially impervious to corrosion and to reaction with the chemicals normally employed in cosmetics, skin creams, and the like, will not contaminate the contents of the container, nor cause a deterioration in the sealing effect thereof.

While I have illustrated preferred embodiments of my invention, modifications may be made without departing from the spirit of the invention, and I do not wish to be

limited to the precise details of construction set forth, but desire to avail myself of all changes within the scope of the appended claims.

I claim:

- 5 1. In combination with a container that includes a body having a neck of circular cross sectional contour projecting from said body, said neck having a coaxial cylindrically sided through bore therein, a cylindrical plug secured within said bore, said plug having a groove formed in one side thereof extending from end to end of said plug axially thereof providing a passageway eccentrically positioned relative to the axis of said bore having a discharge end at the outer end of said neck relative to said body, a cap swivelly secured to said neck for rotation relative thereto about the axis of said bore, said cap including a wall extending over said plug and the outer end of said neck formed with an opening positioned eccentrically of the outer open end of said passageway for movement into and out of registration with said open outer end upon rotating said cap relative to said neck about the axis of said bore.
- 10 2. In combination with a container that includes a body having a neck of circular cross sectional contour projecting from said body, said neck having a coaxial cylindrically sided through bore therein, a cylindrical plug secured within said bore, said plug having a groove formed in one side thereof extending from end to end of said plug axially thereof providing a passageway eccentrically positioned relative to the axis of said bore having a discharge end at the outer end of said neck relative to said body, a cap swivelly secured to said neck for rotation relative thereto about the axis of said bore, said cap including a wall extending over said plug and the outer end of said neck formed with an opening positioned eccentrically of the outer open end of said passageway for movement into and out of registration with said open outer end upon rotating said cap relative to said neck about the axis of said bore.
- 15 3. In combination with a container that includes a body having a neck of circular cross sectional contour projecting from said body, said neck having a coaxial cylindrically sided through bore therein, a cylindrical plug secured within said bore, said plug having a groove formed in one side thereof extending from end to end of said plug axially thereof providing a passageway eccentrically positioned relative to the axis of said bore having a discharge end at the outer end of said neck relative to said body, a cap swivelly secured to said neck for rotation relative thereto about the axis of said bore, said cap including a wall extending over said plug and the outer end of said neck formed with an opening positioned eccentrically of the outer open end of said passageway for movement into and out of registration with said open outer end upon rotating said cap relative to said neck about the axis of said bore.
- 20 4. In combination with a container that includes a body having a neck of circular cross sectional contour projecting from said body, said neck having a coaxial cylindrically sided through bore therein, a cylindrical plug secured within said bore, said plug having a groove formed in one side thereof extending from end to end of said plug axially thereof providing a passageway eccentrically positioned relative to the axis of said bore having a discharge end at the outer end of said neck relative to said body, a cap swivelly secured to said neck for rotation relative thereto about the axis of said bore, said cap including a wall extending over said plug and the outer end of said neck formed with an opening positioned eccentrically of the outer open end of said passageway for movement into and out of registration with said open outer end upon rotating said cap relative to said neck about the axis of said bore.
- 25 5. In combination with a container that includes a body having a neck of circular cross sectional contour projecting from said body, said neck having a coaxial cylindrically sided through bore therein, a cylindrical plug secured within said bore, said plug having a groove formed in one side thereof extending from end to end of said plug axially thereof providing a passageway eccentrically positioned relative to the axis of said bore having a discharge end at the outer end of said neck relative to said body, a cap swivelly secured to said neck for rotation relative thereto about the axis of said bore, said cap including a wall extending over said plug and the outer end of said neck formed with an opening positioned eccentrically of the outer open end of said passageway for movement into and out of registration with said open outer end upon rotating said cap relative to said neck about the axis of said bore.
- 30 6. In combination with a container that includes a body having a neck of circular cross sectional contour projecting from said body, said neck having a coaxial cylindrically sided through bore therein, a cylindrical plug secured within said bore, said plug having a groove formed in one side thereof extending from end to end of said plug axially thereof providing a passageway eccentrically positioned relative to the axis of said bore having a discharge end at the outer end of said neck relative to said body, a cap swivelly secured to said neck for rotation relative thereto about the axis of said bore, said cap including a wall extending over said plug and the outer end of said neck formed with an opening positioned eccentrically of the outer open end of said passageway for movement into and out of registration with said open outer end upon rotating said cap relative to said neck about the axis of said bore.
- 35 7. In combination with a container that includes a body having a neck of circular cross sectional contour projecting from said body, said neck having a coaxial cylindrically sided through bore therein, a cylindrical plug secured within said bore, said plug having a groove formed in one side thereof extending from end to end of said plug axially thereof providing a passageway eccentrically positioned relative to the axis of said bore having a discharge end at the outer end of said neck relative to said body, a cap swivelly secured to said neck for rotation relative thereto about the axis of said bore, said cap including a wall extending over said plug and the outer end of said neck formed with an opening positioned eccentrically of the outer open end of said passageway for movement into and out of registration with said open outer end upon rotating said cap relative to said neck about the axis of said bore.
- 40 8. In combination with a container that includes a body having a neck of circular cross sectional contour projecting from said body, said neck having a coaxial cylindrically sided through bore therein, a cylindrical plug secured within said bore, said plug having a groove formed in one side thereof extending from end to end of said plug axially thereof providing a passageway eccentrically positioned relative to the axis of said bore having a discharge end at the outer end of said neck relative to said body, a cap swivelly secured to said neck for rotation relative thereto about the axis of said bore, said cap including a wall extending over said plug and the outer end of said neck formed with an opening positioned eccentrically of the outer open end of said passageway for movement into and out of registration with said open outer end upon rotating said cap relative to said neck about the axis of said bore.
- 45 9. In combination with a container that includes a body having a neck of circular cross sectional contour projecting from said body, said neck having a coaxial cylindrically sided through bore therein, a cylindrical plug secured within said bore, said plug having a groove formed in one side thereof extending from end to end of said plug axially thereof providing a passageway eccentrically positioned relative to the axis of said bore having a discharge end at the outer end of said neck relative to said body, a cap swivelly secured to said neck for rotation relative thereto about the axis of said bore, said cap including a wall extending over said plug and the outer end of said neck formed with an opening positioned eccentrically of the outer open end of said passageway for movement into and out of registration with said open outer end upon rotating said cap relative to said neck about the axis of said bore.
